ELEVATOR DOOR OPERATOR

Harold V. McCormick, Wilmette, Ill., assignor to
Westinghouse Electric Elevator Company, Chi-
cago, Ill., a corporation of Illinois

Application May 14, 1937, Serial No. 142,640

1 Claim. (Cl. 268—59)

My invention relates to elevator door operators and more particularly to operators for elevator doors having an upper door section and a lower door section vertically and oppositely movable 5 on a pair of guides by a pair of flexible connectors.

The construction and operation of counterbalanced hatchway doors is old and well known in the art but where very wide doors are used, 10 as in freight elevators, and particularly in garages, considerable difficulty has been experienced in providing door operators which will effect the raising or lowering of the door sections in a smooth and efficient manner without causing 15 them to tilt to one side and wedge or stick on their guides.

One object of the invention is to provide an operator or vertically mounted counterbalanced doors which will raise or lower the door sections 20 without causing any binding of the doors on their guides.

Another object of the invention is to provide for counterbalanced doors, an individual operator which may be mounted approximately between the guides for the doors and in which each element will be sufficiently short to prevent backlash or other lost motion which might impair the efficiency of the door operator.

It is also an object of the invention to provide 30 a door operator which is very simple and inexpensive to construct, install and maintain in operation.

For a better understanding of the invention, reference may be had to the accompanying 35 drawings, in which

Figure 1 is a top plan view, partly in section, of an elevator door operator embodying my invention, as installed at a landing in an elevator hatchway.

Fig. 2 is a view of the door operator and counterbalanced door illustrated in Fig. 1 as they appear from the interior of the elevator hatchway;

Fig. 3 is a top plan view, partly in section, of a modification of the door operator illustrated in Fig. 1;

Fig. 4 is a front elevational view of a modified form of the driving means for the door operator illustrated in Fig. 3;

Fig. 5 is a top plan view, partly in section, of another form of the door operator illustrated in Fig. 1; and,

Fig. 6 is a front elevational view of the driving means illustrated in Fig. 5.

Referring more particularly to Figs. 1 and 2 of 55 the drawings, a portion of an elevator car C is

shown in Fig. 1 as disposed opposite a hatchway floor landing 11 represented by the hatchway walls 12.

The hatchway opening 11 is provided with a hatchway door 18 comprising an upper door section 19 and a lower door section 20 mounted upon a pair of vertical guides 21 and 22 by means of a plurality of guide clips 23. The door is of the counterbalanced type in which the door sections move vertically and oppositely upon the 10 guides when the door is being opened or closed. The means for connecting the door sections for their counterbalanced operation comprises a pair of flexible chain or cable connectors 25 and 26, the inner ends of which are fastened to clevis 15 27 and a clevis 28 disposed on clips 29 and 30 attached to the lower outside edges of the upper door section. The center portion of the cable 25 passes outwardly over a first balancing sheave 31 to where its outer end is attached by means of 20 a clevis 32 to the outer end of a bar 33 secured to the upper portion of the lower door section 20, as by a plurality of bolts 36. The middle portion of the cable 26 passes outwardly over a second balancing sheave 34 to where its outer end 25 is attached by a clevis 35 to the right-hand end of the bar 33.

With this construction, it will be seen that the doors are suspended on the sheaves by the flexible connectors and that the weight of the upper 30 door section tends to counterbalance the weight of the lower door section. Hence, by rotating the sheaves, the connectors may be caused to move the door sections in opposite directions to either open or close the door.

In providing operators for very large doors, where the doors are say ten to fifteen or twenty feet wide, the doors have a tendency to stick on their guides or the door operating mechanism develops too much lost motion or backlash for 40 smooth and efficient operation. In order to overcome these difficulties, I have provided for rotating the sheaves by a means comprising a motor 37 mounted approximately midway between the door guides and a suitable operating mecha- 45 nism 38 for connecting the motor to the sheaves for operating the doors in accordance with the operation of the motor. As illustrated in Fig. 1, the motor 37 may be mounted in an aperture or hole 39 in the hatchway wall 12 at a point ap- 50 proximately central of the door guides by means of a tube like projection of the motor end bell 40 which may be secured to the hatchway wall 12 by a plurality of suitable bolts 41. In the operator shown, the motor is disposed on the wall 55

- of the corridor at that landing, but inasmuch as this door operator is provided mainly for garage and freight elevators, the position of the motor in the corridor will not be objectionable and the space which is usually required in the hatchway for housing the motors of the door operators will not be required. Hence, there will be a saving in construction of the hatchways where door operators of the present character are employed.
- 10 The operating mechanism 38 comprises a first gear wheel 43 mounted upon a stub shaft 44 and a second gear wheel 45 mounted upon a stub shaft 46. The shafts 44 and 46 are mounted by suitable bases 47 upon a cross frame 48 or portion of the hatchway wall. The supporting bases are placed close together so that the gear wheels 43 and 45 mesh with each other to cause them to rotate in opposite directions when either one of them is rotated.
- 20 The motor 37 is provided with a pinion 50 that is disposed to engage the gear wheel 43 so that rotation of the motor in the direction of the arrow 51 will cause the gear wheel 43 to rotate in the direction of the arrow 52 and the gear wheel 46 to rotate in the direction of the arrow 53. A driving pulley 54 is secured to the gear wheel 43 on the shaft 44. A belt 55 is disposed upon the pulley 54 in position to extend to and around a driven pulley 56 mounted on a shaft 57 for supporting the sheave 31. The shaft 57 is supported by a bracket 58 on the hatchway wall at the landing 11. Inasmuch as the pulley 56 and the sheave 31 are fixed on the shaft 57, rotation of the pulley 54 by its gear wheel 43 will cause the pulley 56 and the shaft 31 to rotate for operating the flexible connector 25 when the door is to be raised or lowered.
- 30 A driving pulley 60 is secured to the gear wheel 45. A belt 61 extends from the pulley 60 to pass over a drive pulley 62 attached to a shaft 63 on which the sheave 34 is fixed. A bracket 64 supports the shaft. Hence rotation of the gear wheel 45 causes the belt 61 to rotate the sheave 34.
- 40 By the foregoing construction, it will be seen that if the motor is rotated in the direction of the arrow 51 (Fig. 2) the pinion 50 will rotate the gear wheel 43 in the direction of the arrow 52. This will rotate the pulley 54 in the direction of the arrow 52, and the belt 55, the pulley 56 and the sheave 31 in the direction of the arrow 66. At the same time, the rotation of the gear wheel 43 in the direction of the arrow 52 will cause the gear wheel 45 and its attached pulley 50 to rotate in the direction of the arrow 53. This causes the belt 61, the pulley 62 and the sheave 34 to rotate in the direction of the arrow 67. Inasmuch as the sheave 31 is rotating in the direction of the arrow 66 and the sheave 34 in the direction of the arrow 67, the flexible connectors 25 and 26 will be operated to raise the door section 19 and lower the door section 20 so that the hatchway opening 11 is opened for entrance to the car C.
- 50 When it is desired to close the hatchway door, the motor 37 is operated in a direction reverse to that of the arrow 51, which causes the gear wheels 43 and 45 to be rotated in directions opposite to each other and opposite to the arrows 52 and 53. This, in turn, causes the belts 55 and 61 to effect the rotation of the sheaves 31 and 34 in directions opposite to the arrows 66 and 67, thereby moving the connectors 25 and 26 to lower the door section 19 and raise the door section 20
- 60 to close the hatchway opening 11.

Referring to Fig. 3 of the drawings, the driving motor 37 therein illustrated is mounted upon a supporting plate 68 on the outside of the wall 12 of the hatchway. The pinion 50 on the motor 37 is disposed to mesh with the gear wheel 43 which, in turn, meshes with the gear wheel 45. The gear wheels are disposed on the outside of the wall instead of the inside of the wall as shown in Fig. 1, and are supported by a pair of shafts 69 and 70 which extend through the wall and have mounted on their inner ends a pair of pulleys 54 and 60. The shafts 69 and 70 are supported in bushings 71 and 72. The drive pulleys 54 and 60 operate the belts 55 and 61 in the same manner as in Fig. 1, and have the additional advantage of requiring a very small space in the case above the door.

Referring now to Fig. 4, the modified form of drive illustrated therein is the same as that of Fig. 3, except that the motor 37 is provided with a pulley or sprocket 73 for driving a chain 74 which extends over a sprocket wheel 75 and under and around a sprocket wheel 76. The sprocket wheel 75 is a substitute for the gear wheel 43 and the sprocket wheel 76 is a substitute for the gear wheel 45, so that the motor 37 may operate the pulleys 54 and 60 by means of a chain drive to effect the same operation of the sheaves 31 and 34, as is provided by the apparatus shown in Fig. 1.

Referring now to Figs. 5 and 6 in this modified form of the door operator the motor 37 is provided with a pulley or sprocket 50b which operates a belt or chain 89 to rotate a sprocket wheel 81. The sprocket wheel 50b and the sprocket wheel 81 are mounted on the outside of the hatchway wall, the wheel 81 being disposed on the end of a shaft 71a which passes through the wall 12 and has on its inner end a pair of driving pulleys 54a and 60a. The wheel 81 and the pulleys 54a and 60a are fixed on the shaft 71a, so that operation of the sprocket 50b causes the driving pulleys to rotate in the same direction. The pulley 60a is provided with a belt 61a which is disposed to engage that pulley and pass over an idler wheel 77 to the driving pulley 62. The pulley 54a is provided with a belt 55 which passes around the driving pulley 56. With this construction, the operation of the motor 37 causes the driving pulleys 56 and 62 to operate the door sections in the same manner as the apparatus illustrated in Fig. 1.

By either one of the foregoing constructions, it will be seen that I have provided a simple and inexpensive elevator door operator, that it may be located in a conveniently accessible position approximately midway between the guides for the hatchway door, that the connecting elements between the motors and the sheaves operated thereby are approximately half the length they would be if the door operator were located at one side or the other of the doors and that consequently there is little room for backlash or lost motion in the door operating apparatus. Furthermore, inasmuch as the power is applied equally and directly to each driving sheave, the door sections will be raised or lowered without undue tilting at either end.

Although I have illustrated and described several specific embodiments of my invention, it is to be understood that other modifications thereof and changes therein may be made without departing from its spirit and scope.

I claim as my invention:

In an operator for a door having an upper sec-

tion and a lower section vertically and oppositely movable on a pair of guides by a pair of flexible connectors to close an opening in a hatchway wall, a sheave mounted adjacent the upper portion of one of the guides for operating one of the connectors, a second sheave mounted adjacent the upper portion of the other guide for operating the other connector, a motor mounted on the outside face of the hatchway wall above the doorway and at approximately the center thereof with the shaft of the motor extending inwardly through the wall, a pinion mounted on the end of the motor shaft inside the wall, a first

gear wheel mounted in mesh with the pinion, a second gear wheel mounted in mesh with said first gear wheel, a first wheel mounted on the shaft of said first gear wheel, a second wheel mounted on the shaft of said second gear wheel, driving means connecting said first wheel to one of said sheaves, and a driving means connecting said second wheel to the other of said sheaves whereby operation of the motor causes the door to open or to close in accordance with the direction of operation of the motor. 5 10

HAROLD V. McCORMICK.
